UNITED STATES PATENT OFFICE.

GEORGE HARPER AND FRANK HOOVER, OF DETROIT, MICHIGAN, ASSIGNEES
TO THE CLOUGH AND WARREN ORGAN COMPANY, OF SAME PLACE.

PIANO-CASE.

SPECIFICATION forming part of Letters Patent No. 372,616, dated November 1, 1887.

Application filed July 8, 1887. Serial No. 243,760. (No model.)

To all whom it may concern:

Be it known that we, GEORGE HARPER and FRANK HOOVER, citizens of the United States, residing at Detroit, in the county of Wayne 5 and State of Michigan, have invented certain new and useful Improvements in Piano-Cases; and we do declare the following to be a full, clear, and exact description of the invention, such as will enable others skilled in the art to 10 to which it appertains, to make and use the same, reference being had to the accompanying drawings, and to the letters and figures of reference marked thereon, which form a part of this specification.

15 The object of this invention is to improve the construction of that class of instruments in which, when the fall-board of an upright piano or like instrument is raised, as in opening the piano, the music-rack in the front of the instrument will be caused to advance or move 20 forward at the bottom, assuming an inclined position for the sheet-music, the parts being so constructed and united that the opening and closing of the fall-board will automatically operate the music-rack. The spring employed 25 in connection with the several parts causes the fall-board to remain depressed when closed, and also to remain in an upright position when elevated, as will be hereinafter set forth.

30 The other feature of this invention relates to the mechanism coupling the crown-board to the case, whereby said board may be forced back under the top or drawn forward, to increase and decrease the sound of the instrument.

35 The essential features of this invention will be indicated particularly in the claims.

In the accompanying drawings, forming a 40 part of this specification, Figure 1 is a perspective of the back face of the upright front of the piano containing our invention. Fig. 2 is an end view, having one of the cheeks removed, showing the position of parts when the fall-board is raised. Fig. 3 is a perspective of the top having the cover removed. Fig. 4 is an end elevation of the top portion 45 having the end face removed.

W indicates the frame or case of the instrument; C, the crown-board; T, the cover or top; 50 K, the key-frame, and D the music-rack. All of said parts are substantially the same as found in instruments of this class, and therefore will require no special mention.

The music-rack D forms the central panel of the front of the instrument, and has on its 55 upper edge blocks 4, which, by hinges 3, are hinged to the back face of the frame.

nn are torsion-springs. Their ends are bent at right angles to the body. One end of each spring is attached to the frame W; the other 60 ends are attached to the music-rack, as shown by dotted lines in Fig. 1. a' are flexible bands passing over said springs to prevent a rattling of said springs. It will be observed that by this construction, as the lower edge of the 55 music-rack is swung outward or forward, said rods will be twisted, and that the tendency of said rods or springs to untwist will cause the music-rack to hang naturally in an upright position, as shown in Fig. 1. Each end of the 70 fall-board A is provided with a circular channel or recess, Z. (See Figs. 1 and 2.)

F is an upright metal bracket, the foot f' of which is firmly attached to the case back of the cheeks B. We employ a bracket, F, at 75 each end of the fall-board. The head S of each bracket lies within the channels Z of the fall-board and is pivoted at a to said fall-board. The channels Z are made sufficiently large, so as to encircle the heads S of said 80 brackets when turning the fall-board up, as shown in Fig. 2. The channels Z thereby bring the outer face of the heads S flush with the ends of the fall-board, allowing the ends of the fall-board to close flush with the face of 85 the cheeks B.

R is a rod or rock-shaft, which is journaled in boxes d at the back of the front of the piano. Said rod extends from one end of the instrument to a point centrally back of the music-rack D, at which point the rod is bent upward 90 at right angles, forming the arm e, the free end of which is bent horizontally and toward the back of the music-rack, forming the step e', which engages with the button or plate t 95 on the music-rack. (See Fig. 1.) The opposite end of said rod is provided with a crank, c, which engages with the head f of the angular lever H. Said lever is pivoted at 6 to the case of the instrument. To its lower end, at i', 100 is pivoted one end of the coupling-rod V. The opposite end of the rod V is pivoted, at i, to the top and back face of the fall-board, as clearly shown in the drawings.

S is a torsion-spring, one end of which is 105 made fast to the case and is covered by a strip

of felting, 2. The other end terminates at a point in front of the arm *e*, where it is bent at right angles, forming the arm *g*, the free end of which is bent horizontally, forming a foot, 5 5, which presses against the arm *e* of the rock-shaft *R*, as clearly shown in Fig. 1.

It will be observed from the foregoing construction that as the operator raises the fall-board *A* the rod *V* will be carried down and 10 backward, forcing the lower end of the lever *H* back, throwing the head *f* up, thereby rocking the shaft *R*, twisting the spring *S*, and throwing the bottom of the music-rack forward, as shown in Fig. 2; that when the fall-board is raised, as shown in Fig. 2, the point *i*, pivoting the rod *V* to the fall-board, stands below the turning points or pivots *a* of said board; that the pressure of the spring *S* on the arm *e* of the rock-shaft *R* causes the back 15 or lower end of the fall-board to be forced forward, thereby forcing the upper edge of the fall-board backward, thereby maintaining the vertical position shown in Fig. 2. It will also be observed that as the fall-board shown in Fig. 20 25 is closed the point *i* of attachment of the rod *V* to said fall-board rises above the pivot or turning points *a* of said fall-board, as clearly shown in Fig. 1, whereby the pressure of the spring *S* causes said fall-board to be depressed 30 when closed.

The object of the springs *n* is to cause the music-rack to swing back into the case and assume a vertical position when the rock-shaft is thrown back by the closing of the instrument, as shown in Fig. 1.

The crown-board *C* at each end slides on horizontal cleats *d*'. To the back of the crown-board, at the longitudinal center, is attached, by hinges *t t*, a folding or guide board, *B'*. Said 40 guide-board is hinged at its opposite edge to a second folding-board, *B''*, which last board, at its opposite edge, is hinged at *V'* to the case or supporting-board, as clearly shown in Figs. 3 and 4.

45 The case or supporting-board *W'* is provided with two studs or stops, *r* and *a''*. (See Fig. 4.)

Both faces of the board *B''* are provided with a pad, *O'*. Said pads strike the lugs *r* and *a''* as the board *B''* is swung forward and backward in sliding the crown-board *C* under the cover and drawing it forward, which is accomplished by the operator grasping the knob *k'* of the crown-board and pushing, when the crown-board *C* will be slid back, as shown in Fig. 3, the board *B'* swinging backward until it strikes the lug *a''*, when the backward movement of the crown-board *C* will be arrested.

To close the opening *N'* when the board *C* is back, as shown by dotted lines in Fig. 4, the 60 operator draws forward on the button *k'*, the board *C* advancing until the guide-board *B''* strikes the stop *r*, when the forward movement of the crown-board will be arrested and the opening *N'* closed, as shown in Fig. 4.

65 The object of having the boards or plates *B'B''* attached to the crown-board is to cause said crown-board, when moving backward and for-

ward, to travel on a true line, both ends moving alike, thereby preventing any binding of parts.

Having thus fully set forth the features of our invention, what we claim as new, and desire to secure by Letters Patent, is—

1. The combination of the case having the brackets *F* attached thereto, the fall-board pivoted at its ends to said brackets, the music-rack, the rod *R*, the lever *H*, and the rod *V*, coupling said lever to the fall-board, substantially as and for the purposes specified.

2. In combination with the brackets *F*, the fall-board having the recessed ends *Z*, pivoted to said brackets, the music-rack, the shaft *R*, the lever *H*, the rod *V*, having one end pivoted to said lever, the other to the top rear edge of the fall-board, and the spring for operating said shaft, as and for the purposes specified.

3. In combination with the brackets *F*, the fall-board, and the channels *Z* in the ends of said fall-board, the heads of said brackets located in said channels and pivoted to the fall-board at *a*, as and for the purposes specified.

4. In combination with the fall-board, the bracket pivoted at *a* to the end thereof, the music-rack, the lever *H*, the rod coupling said lever to the music-rack, and the rod *V*, having one end coupled to said lever, the other end to the fall-board, whereby the pivoted point *i* will travel in the arc of a circle about the pivot *a* in raising and lowering the fall-board, as and for the purposes specified.

5. In combination with the brackets, the fall-board pivoted at its ends to said brackets, the music-rack having the torsion-spring *n*, the lever *H*, pivoted to the case, the rod coupling said lever with the music-rack, a spring 105 pressing said rod, and the rod *V*, pivoted at one end to the lower end of said lever, its other end to the back of the fall-board, as and for the purposes specified.

6. The combination of the swinging fall-board, the swinging music-rack, the angular lever, the rod coupling said lever to the fall-board, and the horizontal rock-shaft having engagement at one end with the angular lever, at the other end with the music-rack, substantially as and for the purposes specified.

7. In combination with the case having the supports *d*', the sliding crown-board, the plates *B'B''*, hinged together, one plate being hinged to the crown-board, the other to the case, substantially as and for the purposes specified.

8. The combination of the case, the supports *d*', the crown-board, the plate *B'*, hinged to the crown-board and to the plate *B''*, the latter plate hinged also to the case, the stops *a''* and *r*, engaging with the plate *B''*, as and for the purposes specified.

In testimony whereof we affix our signatures in presence of two witnesses.

GEORGE HARPER.
FRANK HOOVER.
